UNITED STATES PATENT OFFICE.

ERNEST B. COBB, OF JERSEY CITY, NEW JERSEY, ASSIGNOR TO STANDARD OIL COMPANY, A CORPORATION OF NEW JERSEY.

PROCESS OF DESULFURIZING PETROLEUM-OILS.

1,357,225.

Specification of Letters Patent. Patented Nov. 2, 1920.

Application filed March 13, 1919. Serial No. 282,288.

To all whom it may concern:

Be it known that I, ERNEST B. COBB, a citizen of the United States, residing at Jersey City, in the county of Hudson and State 5 of New Jersey, have invented certain new and useful Improvements in Processes of Desulfurizing Petroleum-Oils, of which the following is a specification.

My invention relates to new and useful 10 improvements in processes for the removal of elementary sulfur from petroleum oils. My present application is a division, in part, of my prior application, Serial No. 50,177, which was filed in the Patent Office on or 15 about September 11, 1915, Patent No. 1,300,816, April 15, 1919. By elementary sulfur I mean that sulfur which exists in the oil in its elementary forms, such as brimstone, flowers of sulfur, and all other modifications 20 of elementary sulfur held in physical solution in the oil. The invention is applicable to and covers the removal of elementary sulfur primarily existing as such in the oil, and also elementary sulfur resulting from acid 25 treatment of the oils and other processes of refining and chemical treatment. The presence of elementary sulfur in petroleum oils may be ascertained by first testing the oil by any of the well-known tests for sulfureted hydrogen (H_2S) and removing the 30 same if any be present by any of the well-known processes for this purpose, after which a piece of bright copper or silver is immersed in the oil freed of sulfureted hydrogen (H_2S) and the oil heated; if any elementary sulfur is present it will act to tarnish or blacken the copper or silver. The removal of sulfureted hydrogen from the 35 test oil is a necessary preliminary because it also darkens copper and silver. But in the treatment of the main body of oil, as hereinafter described, it is unnecessary to remove the sulfureted hydrogen by preliminary treatment.

I have discovered that elementary sulfur existing in petroleum oils, either primarily, or as the result of treatments, or reactions, with other compounds, or elements, may be removed by treatment with sulfids of the 50 alkaline earths. By sulfids I refer particularly, although not necessarily, or by way of limitation, to monosulfids—that is to say, for example, calcium sulfid (CaS), etc.

It is well known that higher sulfids of 55 these metals, such as calcium, exist, and the

chemical action in using sulfids thereof, as contemplated by my invention, is to cause removal of the elementary sulfur apparently by simple addition, the sulfur combining with the low sulfids of the alkaline earth 60 metal to produce higher sulfids.

By sulfids of the alkaline earth metals, I mean sulfids of the alkaline earth metal group, but in practice I preferably use sulfids of lime, although I do not necessarily 65 exclude any of the sulfids of the alkaline earth metal group.

My invention may be carried out either by filtering the oil through an alkaline earth sulfid under proper conditions, or by agitating 70 the sulfid with the oil.

In the drawings in which like reference numerals indicate like parts, Figures 1 and 2 illustrate an apparatus for carrying out the filtering process with alkaline earth sulfids, Fig. 1 being a side elevation, and Fig. 2 a section of the lower portion of the tank, and Fig. 3 is a side view, partially broken away, of an apparatus for carrying out the agitation process with alkaline earth sulfids. 75

In Figs. 1 and 2 I show an apparatus for filtering the oil through a sulfid of an alkaline earth metal, and this is the preferred method of carrying out my invention. This apparatus includes a vertically disposed 85 cylinder or tank 30, adapted to contain the oil to be desulfurized, a feed pipe 31, entering the upper portion of the cylinder to feed the oil to the latter. The cylinder is provided with an upper head 32, and a lower head 33, the former being provided with a manhole 34. The lower head is provided with a central opening 35 discharging into a neck 36, bolted to said head, and closed at its lower end by a removable cover plate 37. 90 The body of the neck is of less diameter than the opening 35, for a purpose to be described, and is provided with an external flange or shell 38 forming with said neck an annular passage 39, having an inclined bottom 40, said passage being accessible to the interior of the cylinder through the annular space 41 afforded between the upper portion of the neck and the edge of the opening 35. The upper edge portion of the flange 38 105 provides convenient means by which the neck may be bolted to the cylinder. A suitable outlet pipe 39a leads from the passage 39.

The bottom head of the cylinder is provided with a false bottom consisting of a 110

layer of wire mesh 42, preferably completely covering said head, and overlying this wire mesh is a layer of canvas 43, or other suitable material, the edges of the latter extending upward for a distance about the circumference of the lower head, as at 44, for a purpose to be presently set forth. Both the mesh and the canvas covering are cut away at the center, as shown, the inner edge 10 of the mesh preferably terminating slightly short of the annular passage 39, while the inner edge of the canvas is carried over said passage and secured to said neck by a clamping ring 45 and bolts 46.

15 The wall of the cylinder is provided with an inwardly projecting annular flange 47, overlying the outer edges of the canvas and wire mesh layers, the space between the said flange and the canvas being packed with cotton or wool waste packing, as at 48. Adjacent its lower end portion the cylinder is provided with a manhole 49 for a purpose to be presently set forth.

20 In carrying out my process, filtering the oil through sulfids of the alkaline earth group, I preferably proceed as follows:

25 800 pounds of freshly burned lime are placed preferably in an open pan or receptacle, into which is poured a mixture of 600 pounds of commercial sulfid of soda and 50 gallons (417 pounds) of water. As the lime slakes there is a decomposition of the sulfid of soda, thereby forming sulfid of lime and caustic soda. Upon the termination of 30 the slaking action the material, *i. e.* the sulfid of lime and caustic soda, should be granular and somewhat coarse. The material is then placed in the chamber of the tank 30 and spread evenly over the false bottom 31 thereof to the proper height, as indicated by 35 the dotted line in Fig. 1 of the drawings. When the material is packed in the tank the impure oil to be desulfurized is pumped in at the top of the tank through the pipe 31, and is permitted to percolate down 40 through the filter-like bed of sulfid of lime. The oil in passing through the sulfid of lime is completely desulfurized by reaction of the sulfur with a sulfid of lime by simple 45 addition to produce higher sulfids, as has been previously set forth. The degree of desulfurization may be determined by the copper test described on samples of the oil taken from the outlet pipe 39^a. The purification 50 in this case may be continued until test samples show no blackening of copper when tested as described, whereupon the exhausted sulfid is removed and the tank is recharged with a fresh supply of sulfid.

55 60 The filtering method above described effects contact between the oil and solid sulfid as distinguished from contact of the oil and liquid sulfid in the process described in my parent application, Serial No. 50,177.

65 65 The two methods are largely interchange-

able, but the filtration method may be used when the chemical and physical character of the oil make it appear desirable to treat the oil with a solid rather than with a liquid, as, for example, when a sample of the oil tends to emulsify when treated with the water solution. The filtering process provides for a systematic use of the active agent; that is, as the operation progresses the raw oil comes in contact with 70 partially exhausted sulfid first, and on passing to the bottom of the filter it meets sulfid of a less and less degree of exhaustion.

75 It will, of course, be understood that the alkaline earth sulfid may be prepared in any 80 desired manner, and that the process outlined above is, therefore, only illustrative. A sulfid of lime may, for example, be prepared in the following manner: 800 pounds of freshly burned lime may be placed in an 85 open pan or receptacle into which is poured 50 gallons of water, the amount of water added being just sufficient to leave the lime in the proper physical condition, neither dusty nor pasty. The material is then introduced into the tank 30 and spread evenly 90 over the false bottom. Sulfureted hydrogen is then introduced into the bottom of the tank which converts the solid lime into calcium monosulfid. The remainder of the 95 process may then be carried out in precisely the same manner as when the calcium sulfid is added to the tank.

100 In Fig. 3 I have shown an apparatus for carrying out the process where the alkaline earth sulfid is agitated with the oil to be treated. In the apparatus there shown, 1 designates a cylinder or receptacle adapted to receive the oil to be treated and having a 105 conical bottom 2 and a dome-shaped top or cover 3, which is preferably provided with doors 50. The conical shaped bottom 2 is provided at its apex with an outlet pipe 4 having a valve 5 at its lowermost portion, through which pipe the contents of the cylinder may be flowed when the valve is open, as will be hereinafter described. A steam 110 inlet pipe 18 enters the tank through the cover 3 and is provided with a depending outlet portion 19, by means of which live steam may be admitted to the interior of the cylinder, an air inlet pipe 20 being connected with pipe 18 and provided with a valve 21, for a purpose to be presently described. The 115 pipe 18 may be provided with a valve 22 for controlling the flow of steam from the pipe to the interior of the cylinder, said pipe being connected with the pipe 18 between the valve 22 and the outlet end of said pipe 18. Also connected to the steam pipe 18 is 120 a pipe 23 leading to a closed heating coil 24, of any suitable form, located within the bottom portion of the cylinder, said coil being provided with a control valve 25 for controlling the flow therethrough. The outlet end 125

of the steam coil, which is indicated by the character 26, is provided with a valve 26^a. A second heating coil 24^a is preferably provided having a valve 24^b at its free end.

5 The inlet pipe for feeding the oil to be treated to the cylinder is shown at 27, the said pipe entering the cylinder adjacent the upper portion thereof and extending to a point preferably within the area of the cone-shaped bottom. The treated oil may be withdrawn from the cylinder through an outlet pipe 28, controlled by a valve 29, said pipe being located at a point on the bottom of the cone-shaped bottom, which will be above 10 the solid material which settles from the oil during the process. The pipe preferably communicates within the cylinder with an adjustable swing pipe 28', which will be adjusted in accordance with the depth of the solid material formed in the bottom of the tank.

15 I do not desire to be limited in any way to an apparatus such as described, having only described the same in detail so as to insure an adequate understanding of the 20 process embodying my invention.

In carrying out the process with the apparatus illustrated in Fig. 3, the alkaline earth sulfid may be prepared in accordance 30 with the method outlined in connection with the apparatus illustrated in Figs. 1 and 2, and after the oil has been placed in the tank the alkaline earth sulfid may be introduced to the oil through the doors 50. Steam 35 is now introduced through the pipes 23, 24 and 24^a in order to warm the oil, the valves at the free ends of the pipes 24 and 24^a being open sufficiently to carry away the condensed water. The oil is heated to a 40 temperature above the condensing point of water, from 212° F. to 300° F. Dry steam is then introduced through the pipe 19 in order to agitate the oil, and then the sulfid of the alkaline earth is introduced through the top 45 of the agitator to the oil. The agitation is continued until a specimen of the oil, when the solid material is settled out, and when the oil is submitted to the copper test, shows that the sample is free from sulfur. If continued 50 agitation does not eliminate all the sulfur, more sulfid of the alkaline earth must be employed. The length of time required for carrying out the process will, of course, depend upon the amount of oil under 55 treatment. With a tank containing 100 barrels of oil, I have found that the treatment can usually be carried out in from one to three hours. When the elementary sulfur has been entirely removed, the steam is shut off and the oil allowed to settle. This settling 60 may require about an hour. When the settling is completed, the oil is drawn off through the adjustable swing pipe 28', and the spent material is washed from the bottom 65 of the tank through the pipe 4, and the

tank is then ready for the treatment of a second batch.

In both of the described processes, namely, the filtering process, and the agitation process, the oil is treated under alkaline conditions. For example, the treatment of lime with commercial sulfid of soda results in the formation of caustic soda, as well as sulfid of lime, and when solid lime is added to the tank and sulfureted hydrogen passed 70 through the same, the lime itself, under ordinary conditions, creates an alkaline condition in the oil. I preferably carry out the process under alkaline conditions for the reason that the alkali neutralizes any acid 75 bodies left in the oil from previous refining processes, and because the material appears to be more active in its action upon the elementary sulfur contained in the oil when the material is alkaline.

80 It is to be understood, however, that under certain conditions, the process may be successfully carried out when the liquid is not alkaline, and my invention, therefore, is not limited to carrying out the process under alkaline conditions.

85 It is also to be understood, that in case objectionable odor or taste remain in the oil after the treatment described above, a suitable washing process may be carried 90 out. In the agitation process shown in Fig. 3, this washing process may be carried out either by injecting steam into the oil through the pipe 19, or the oil may be washed with water in a well known manner. The apparatus shown in Figs. 1 and 2 does not lend 95 itself to the washing process, and in case the oil under treatment in the filtering process needs to be washed, the oil should be transferred to a suitable receptacle where 100 the washing process may be carried out. Inasmuch as the treatment above described, however, will ordinarily produce oil that requires no washing, and since the washing process is one that is well understood in the 105 art, I have not shown the apparatus necessary for carrying out this washing process.

110 What I claim and desire to secure by Letters Patent of the United States is:

1. The process of removing elementary 115 sulfur from petroleum oil, which consists in subjecting said oil to an alkaline earth sulfid.

2. The process of removing elementary 120 sulfur from petroleum oil, which consists in subjecting said oil to an alkaline earth sulfid, and continuing the treatment until the treated oil ceases to have a darkening effect on metallic copper.

3. The process of removing elementary 125 sulfur from petroleum oil, which consists in treating said oil with an alkaline earth sulfid accompanied by heat at a temperature of from 212° to 300°.

4. The process of removing elementary 130

sulfur from petroleum oil, which consists in subjecting said oil to an alkaline earth sulfid under alkaline conditions.

5. The process of removing elementary sulfur from petroleum oil, which consists in filtering the oil through a body of an alkaline earth sulfid.

6. The process of removing elementary sulfur from petroleum oil, which consists in 10 filtering the oil through a body of calcium sulfid.

7. The process of removing elementary sulfur from petroleum oil, which consists in subjecting said oil to the action of calcium sulfid.

15. 8. The process of removing elementary sulfur from petroleum oil, which consists in filtering the oil through a body of an alka-

line earth sulfid, and continuing the process until the treated oil ceases to have a dark- 20 ening effect on metallic copper.

9. The process of removing elementary sulfur from petroleum oil, which consists in subjecting said oil to a material formed from the following materials in substantially the following proportions: lime 800 pounds, sulfid of soda 600 pounds, and water 50 gallons.

In testimony whereof I have hereunto signed my name in the presence of two sub- 30 scribing witnesses.
